APPARATUS FOR FEEDING FILLER TOBACCO
TO CIGAR MACHINESFranz Heinrich Benno Stelzer, Dresden, Germany,
assignor, by mesne assignments, to J. C. Muller,
N. V., Rotterdam, NetherlandsApplication August 24, 1938, Serial No. 226,457
In Germany September 3, 1937

6 Claims. (Cl. 131—21)

The present invention relates to a device for feeding filler tobacco for cigar machines and more particularly to the type of feeding device in which the loose tobacco is fed by means of a conveyor belt.

An object of the present invention is to control the operation of the conveyor belt by a feeler device associated with the filler forming part of the machine.

A further object is to provide means for controlling the feeding of filler tobacco so as to produce fillers of uniform quality.

In general the invention resides in controlling the tobacco delivered to the filler forming device from the conveyor according to the amount of tobacco present in the filler forming device. The invention is applied, in one instance, to a machine in which the conveyor belt is operated by a pawl and the swinging of this pawl is subject to be interrupted at times when the filler forming device contains an over abundance of tobacco.

With the foregoing and other objects in view, the invention will be more fully described hereinafter, and will be more particularly pointed out in the claims appended hereto.

In the drawing, wherein like symbols refer to like or corresponding parts throughout the several views.

Figure 1 is a longitudinal vertical section taken through the part of the machine to which the invention is applied.

Figure 2 is a fragmentary detail of the conveyor mechanism of Figure 1, and

Figure 3 is a fragmentary detail view of part of the automatic control mechanism of Figure 1.

An endless conveyor belt 1 is entrained over the drive roller 3 and extends to a suitable source of filler tobacco. Tobacco is deposited upon the upper run of the belt 1 in the form of a fleece or layer 2. The roller 3 is drivingly mounted upon a shaft 4 which carries at one end a ratchet wheel 8. A lever 5 is pivoted freely upon the shaft 4 and carries at its upper end a pawl 6 mounted on a pin 7. The upper end of the lever 5 is also attached to a traction spring 9 which biases it towards the adjustable stop 10 which is mounted on the frame of the machine. The lower end of the lever 5 is provided with a pin 11 which engages in a slot 12 of the arm 13. The opposite end of the arm 13 is mounted in a hollow collar 14, the pin 16 of the arm 13 sliding in the slot 17 of the collar. Another arm 15 has its upper end extending into the collar 14 in which position it is fixed. A spring 18 is fas-

tened at 19 to the collar 14 and at its opposite end to the pin 16 of the arm 13. This arrangement provides a yielding connection between the two arms 13 and 15. The arm 15 is pivoted at 21 to one branch of the three armed lever 22 which is pivoted at 23 on the machine and carries a roller 24 at the end of another branch. The roller 24 is held against the surface of a cam 26 by means of the spring 25. The cam 26 is fastened upon the driven shaft 27. It will be seen that when the shaft 27 is driven to rotate the cam 26 the three armed lever 22 will be given an intermittent swinging motion which will normally have the effect of driving the pawl 6 to rotate the ratchet wheel 8 and the roller 4 to advance the conveyor 1. The ratchet wheel 8 is provided with the pawl 20 to prevent clockwise rotation.

The arm 13 of the conveyor driving means is provided with a stop pin 28 against which the lever 29 is mounted to swing. The lever 29 is fastened upon the shaft 31 which has also fastened to it the lever 30. The lever 30 is pivotally secured to a link 32 which connects it to the upper part of a bell crank lever 33. This bell crank lever 33 is pivotally mounted at 34 and carries at the outer end of its other arm a roller 35 which is biased by the spring 36 to ride upon the surface of the cam 37. The cam 37 is drivingly mounted upon the driven shaft 27. It will be apparent that a counterclockwise swinging of the lever 33 will advance the lever 29 against the stop pin 28 of the arm 13 so that in this position the arm 13 is held in its uppermost position and movement of the arm 15 will not be transmitted to the pawl driving mechanism, the spring 18 yielding to permit sliding in the collar 14.

Tobacco delivered from the top run of the belt 1 passes through the rollers 42 and 43, shown in Figure 2, and thence upon the inclined plate 44 into the chute 45. The roller 42, which is provided with teeth, is rotated in the direction of the arrow to make the thickness of the tobacco layer 2 of uniform dimension. The roller 43, which is likewise toothed, is driven in the direction of the arrow to break up the forward edge of the tobacco layer 2 as it passes over the delivery point. The tobacco falling through the chute 45 is delivered over the opening 46 of the filler forming channel 47. The opening 46 is guarded by a swinging gate 48 pivoted at 49 and controlled by the link 50 which is periodically actuated to swing the gate 48 to open position to uncover the opening 46. The forming of the

tobacco filler is accomplished by the use of the plunger 51 which is reciprocated in the channel 47 by means later to be described. In Figure 1, the plunger 51 is in advanced position. When the plunger 51 is retracted and the gate 48 is lifted tobacco delivered from the chute 45 is deposited in front of the pressing end of the plunger and upon the return movement of the plunger such tobacco is pressed into the opposite end of the channel 47 where it forms a compact filler V. At suitable intervals a knife 53 is operated to sever portions of proper size for individual cigar fillers.

The plunger 51 is driven by the link 55 which is pivoted at 54 thereto. At 56 the link 55 is pivoted to the end of a bell crank lever 57 which is swingably mounted at 58 upon the machine. The other arm of the bell crank lever carries the roller 60 which is biased against the surface of the cam 61 by means of a spring 59. The cam 61 is drivingly mounted upon the drive shaft 27 along with the other cams before described. The pivot 56 also connects a slotted bar 62 with the plunger operating mechanism. An arm 65 pivoted at 66 carries at its lower end a pin 64 upon which is mounted a roller 68 (Figure 3). The pin 64 extends through the slot of the bar 62 and reciprocation of the link 55 is accompanied with swinging of the arm 65 in the roller 68. The arm 65 is braked so as to resist free movement by means of a spring pin 67 which frictionally engages against the frame of the machine.

The bell crank lever 33, previously described, has a lateral projection 38 to which is fastened by bolts 39 or the like an arm 40. The free end of the arm 40 is provided with an enlargement the lower surface of which is preferably given a curved shape. The enlargement on the arm 40 is disposed to rest in its raised position upon the roller 68 carried by the arm 65. It will be seen that when the roller 68 is beneath the enlargement on the arm 40 the bell crank lever 33 is held in the solid line position of Figure 1 even though the low part of the cam 37 is presented beneath the roller 35. When, however, the arm 65 and roller 68 assume the position marked 68' the roller 68 passes from beneath the enlargement of the arm 40 and the lever 33 is then free to assume the dotted line position of Figure 1 when the low part of the cam 37 is presented. Since the movement of the arm 65 and roller 68 is controlled by the link 55 it will be seen that the position of the roller with respect to the arm 40 depends upon the position of the plunger 51 in the filler forming channel 47. When a small quantity of tobacco is present in the channel 47, as shown in Figure 1, the plunger 51 is advanced to the left and the roller 68 will be disposed beneath the enlargement of the arm 40 (Figure 3). In this position the lever 29 will be held in its solid line position and the feeding of tobacco will be uninterrupted. When a greater quantity of tobacco is present in the channel 47 the plunger 51 cannot advance so far and eventually a position will be reached in which the roller 68 is not placed beneath the enlargement of the arm 40. When this occasion arises the lever 33 will be released to swing under the force of the spring 36 to place the lever 29 against the stop pin 28 of the arm 13 and further feeding of the conveyor belt 1 prevented.

The tobacco feeding mechanism also includes a flap valve 70 pivoted at 71 in the chute 45. This flap is controlled by the arm 72 and link 73 which

in turn is pivoted at 74 to the third arm 75 of the three branched lever 22. The feeding action of the pawl 6 is therefore synchronized with the opening and closing of the flap valve 70. The operation of the valve 70 is not however affected by the position of the lever 29.

In the operation of the device the shaft 27 is driven from any suitable source and tobacco is deposited upon the upper run of the belt 1. When the shaft 27 is driven counterclockwise, as shown by the arrow in Figure 1, the cam 26 revolves and the high point of the cam strikes the roller 24 once in every revolution to swing the lever 22 in the direction of the arrow. This swinging normally occasions an advance in the ratchet wheel 8 and a corresponding advance of the conveyor belt 1. The flap valve 70 is also opened and any accumulated tobacco is dropped through the chute 45. At the same time the cam 61 is being rotated the high part 69 strikes the roller 60 before the flap valve 70 is opened. The plunger 51 is therefore withdrawn from beneath the opening 46. As soon as the pressing edge of the plunger 51 clears the opening 46 the gate 48 is swung to open position by means of a suitably timed cam or other obvious mechanism. The tobacco dropping from the valve 70 therefore falls into the forming channel 47. The flap 70 is only opened for a brief interval due to the small size of the high part of the cam 26 and it is immediately closed again. The gate 48 is then swung closed and the low part 76 of the cam 61 is brought beneath the roller 60. The tension of the spring 59 thereupon forces the plunger 51 to press tobacco into the forming end of the channel 47. The bell crank lever 33 executes its function.

The belt 1 and the feed mechanism therefor are proportioned to handle a slight excess of tobacco so as to insure at all times that a complete filler is formed. When the tobacco is delivered normally to the belt 1 an excess will accumulate and eventually the plunger 51 will be unable to advance sufficiently to place the roller 68 beneath the enlargement of the arm 40. When this time arises feeding of the belt is momentarily suspended until the mass of tobacco in the channel 47 is formed, cut off and removed. Thereupon normal feeding is again established without interruption.

It is obvious that various changes and modifications may be made in the details of construction and design of the above specifically described embodiment of this invention without departing from the spirit thereof, such changes and modifications being restricted only by the scope of the following claims.

What is claimed is:

1. A tobacco feeding device comprising a continuous tobacco conveyor, a pawl and ratchet drive for said conveyor, a driven cam, a lever swingably mounted for operation by said cam, an arm connected to be moved with said lever, a second arm connected to said pawl and ratchet drive, a resilient driving connection between said arms whereby to operate said conveyor from said cam, and means for interrupting the feeding of said conveyor including a stop for said second arm.

2. A tobacco feeding device comprising a continuous tobacco conveyor, a pawl and ratchet drive for said conveyor, a driven cam, a lever swingably mounted for operation by said cam, an arm connected to be moved with said lever, a

second arm connected to said pawl and ratchet drive, a resilient driving connection between said arms whereby to operate said conveyor from said cam, filler forming means, and conveyor controlling means operable by the presence of an excess of tobacco in said forming means and including a stop operable to engage said second arm upon the presence of an excess of tobacco in said forming means to interrupt feeding of said conveyor.

3. A tobacco feeding device comprising a continuous tobacco conveyor, pawl and ratchet drive for said conveyor, a driven cam, a lever swingably mounted for operation by said cam, an arm connected to be moved with said lever, a second arm connected to said pawl and ratchet drive, a resilient driving connection between said arms whereby to operate said conveyor from said cam, filler forming means, said forming means including a reciprocable plunger, a conveyor interrupting stop lever for engagement with said second arm, means for operating said interrupting lever to place it in operating position, and coordinating means between said reciprocable plunger and the operating means for said interrupting lever for rendering said operating means operable only upon the presence of an excess of tobacco in said forming means.

4. In a machine of the class described having a tobacco filler forming mechanism including a filler forming channel, and a plunger adapted to reciprocate in said channel; a device for feeding tobacco to said channel, comprising a conveyor, a pawl and ratchet drive for said conveyor, a driven cam, swingable means operatively connected to said cam, an arm connected to said swingable means and movable with the latter, a second arm connected to said pawl and ratchet drive, resilient means operatively connecting both of said arms together whereby said conveyor is operated by said driven cam, and means cooperating with said filler forming mechanism for interrupting movement of said second arm upon the presence of an excess of tobacco in said channel.

5. In a machine of the class described having a tobacco filler forming mechanism including a

filler forming channel, and a plunger adapted to reciprocate in said channel; a device for feeding tobacco to said channel, comprising a conveyor, a pawl and ratchet drive for said conveyor, 5 a driven cam, swingable means operatively connected to said cam, an arm connected to said swingable means and movable with the latter, a second arm connected to said pawl and ratchet drive, resilient means operatively connecting 10 both of said arms in end-to-end relation, whereby said conveyor is operated by said driven cam, means movable into engagement with said second arm to interrupt movement of the latter, and a feeler mechanism cooperating with said plunger for moving said last named means into engagement with said second arm upon the presence of an excess of tobacco in said channel.

6. In a machine of the class described having a tobacco filler forming mechanism including a 20 filler forming channel and a plunger adapted to reciprocate in said channel; a device for feeding tobacco to said channel comprising an endless conveyor, a pawl and ratchet drive for said conveyor, a driven cam, a swingable lever operatively connected to said cam, an arm connected to said swingable lever and movable with the latter, a second arm connected to said pawl and ratchet drive, resilient means operatively connecting both of said arms together whereby said conveyor is operated by said driven cam, an abutment member on said second arm, a pivoted lever adapted to cooperate with said abutment member to interrupt movement of said second arm, a second driven cam coordinated with said first 25 named driven cam, link means adapted to operatively connect said second named driven cam and said pivoted lever, and a cam member on said link means cooperating with said plunger, and operable to disconnect said link means from said second named driven cam upon the presence in said channel of an insufficient quantity of tobacco, whereby said pivoted lever is moved by said second named driven cam to avoid co-operation with said abutment member to permit 30 the feeding of tobacco.
